COMBINED DISPLAY CONTAINER AND TOTE BAG

Ned H. Gallasch, Milwaukee, Wis., assignor to ABC
Industries, Inc., Milwaukee, Wis.

Filed Dec. 20, 1972, Ser. No. 306,360

Term of patent 14 years

Int. Cl. D3—01

U.S. Cl. D87—5 G

FIG. 1.

FIG. 2.

FIG. 1 is a perspective view of a combined display container and tote bag showing my new design; and

FIG. 2 is a perspective view showing the side and end not shown in FIG. 1.

The bottom is substantially plain and unornamented.

I claim:

The ornamental design for a combined display container and tote bag, as shown and described.
